US00D448242B1

(12) **United States Design Patent** (10) Patent No.: **US D448,242 S**
McDonough et al. (45) Date of Patent: ** Sep. 25, 2001

(54) **TRAINER CUP**

- (75) Inventors: **Justin E. McDonough**, Kenvil, NJ (US); **Steve Aridgides**, Yardley, PA (US)
- (73) Assignee: **Johnson & Johnson Consumer Companies, Inc.**, Skillman, NJ (US)
- (**) Term: **14 Years**
- (21) Appl. No.: **29/124,904**
- (22) Filed: **Jun. 12, 2000**

Related U.S. Application Data

- (63) Continuation-in-part of application No. 29/116,372, filed on Dec. 30, 1999.
- (51) **LOC (7) Cl.** **07-01**
- (52) **U.S. Cl.** **D7/509**; D7/514; D7/532
- (58) **Field of Search** D7/507, 509, 623, D7/510, 511, 624, 606, 625, 619, 514, 515, 518, 529, 530, 531, 532; 220/669, 713; 206/517, 519, 520

(74) Attorney, Agent, or Firm—Michele G. Mangini

(57) **CLAIM**

The ornamental design for a trainer cup, as shown.

DESCRIPTION

FIG. 1 is a perspective view of a first embodiment of a trainer cup showing our new design;
FIG. 2 is a front elevational view of the first embodiment;
FIG. 3 is a rear elevational view of the first embodiment;
FIG. 4 is a right side elevational view of the first embodiment;
FIG. 5 is a left side elevational view of the first embodiment;
FIG. 6 is a top plan view of the first embodiment;
FIG. 7 is a bottom plan view of the first embodiment;
FIG. 8 is a perspective view of a second embodiment of a trainer cup showing our new design;
FIG. 9 is a front elevational view of the second embodiment;
FIG. 10 is a rear elevational view of the second embodiment;
FIG. 11 is a right side elevational view of the second embodiment;
FIG. 12 is a left side elevational view of the second embodiment;
FIG. 13 is a top plan view of the second embodiment; and,
FIG. 14 is a bottom plan view of the second embodiment.

1 Claim, 8 Drawing Sheets
